UNITED STATES PATENT OFFICE.

LADISLAUS PREICZER, OF PITTSBURGH, PENNSYLVANIA.

LIFE-BOAT.

1,105,303.

Specification of Letters Patent.

Patented July 28, 1914.

Application filed February 18, 1914. Serial No. 819,532.

To all whom it may concern:

Be it known that I, LADISLAUS PREICZER, a subject of the King of Hungary, residing at Pittsburgh, in the county of Allegheny 5 and State of Pennsylvania, have invented certain new and useful Improvements in Life-Boats, of which the following is a specification, reference being had therein to the accompanying drawing.

10 This invention relates to life boats and has for its object to provide a boat of such class, in a manner as hereinafter set forth, with means to prevent the capsizing of a boat, and further with means to maintain 15 the boat in an upright position when traveling through a heavy surf.

Further objects of the invention are to provide a life boat which is comparatively simple in its construction and arrangement, 20 strong, durable, efficient and convenient in its use, readily set up, and inexpensive.

With the foregoing and other objects in view the invention consists of the novel construction, combination and arrangement of 25 parts as hereinafter more fully described and illustrated in the accompanying drawings, wherein is shown an embodiment of the invention, but it is to be understood that changes, variations and modifications can be 30 resorted to which come within the scope of the claims hereunto appended.

In describing the invention in detail reference is had to the accompanying drawings wherein like reference characters denote 35 corresponding parts throughout the several views, and in which:—

Figure 1 is a transverse sectional view of a life boat in accordance with this invention; Fig. 2 is a side elevation, broken away; 40 Fig. 3 is a sectional detail of a rocking arm.

Referring to the drawings in detail 3 denotes the hull of a vessel which is provided with a solid keel 4, with this exception, that the keel centrally thereof is formed with a 45 transverse opening 5. Each side of the hull 3 is formed with a vertically disposed pocket 6 which at its lower end communicates with an opening 5 and at its upper end communicates with an opening 7. Arranged within 50 each of the pockets 6, in proximity to the opening 7, is a horizontally disposed eye 8 for the purpose to be presently referred to. The inner wall of each of the pockets 6, at its lower end, diverges, as indicated at 9, 55 whereby the lower end of each of the pock-

ets 6 is of greater width than the upper portion of the pocket. Attached to the hull 3, centrally thereof, and depending into the opening 5, is a hanger 10, carrying an annular member or link 11, to which is loosely connected a suspension arm 12, the latter being provided intermediate its ends with an opening 13. Attached to the lower end of the arm 12 is an annular link 14, to which is loosely connected a weight 15. Arranged 60 in each of the pockets 6, and extending through an eye 8, is a vertically disposed rod 16, having a head 17, the latter engaging the eye 8 to arrest downward movement of the rod 16. The lower end of each of 70 the rods 16 curves inwardly as at 18, and the said end 18 extends between the bifurcated upper end 20 of a rocking arm 21. The end 18 of the rod 16 is pivotally connected to the bifurcated end 20, of the rocking arm 75 21, by a pin 22. Each of the rocking arms 21 are curvilinear in contour and ride against the faces of the arm 12. Each of the rocking arms is provided with an opening 21^a and extending through said openings is a 80 curved bar 23 which connects the lower portions of the rocking arms together. The bar 23 extends loosely through the openings 21^a and is formed with downwardly bent ends 24 which ride against rollers 25 arranged within the opening 21^a of the rocking arms 21. The rocking arms 21 are furthermore pivotally mounted upon bars 26 seated in the keel and extend across the opening 5.

When the hull of a vessel swings, due to 90 swell of the waves or heavy surf, it will assume the position shown in dotted lines in Fig. 1, or such action will be had against the action of the weight 15 and arm 12, and as the arm 12 will always remain in a vertical position, it is obvious that the rocking arms will be shifted, tending to resist the overthrowing or capsizing of the boat, and under such conditions reduce capsizing to a minimum. The action of the rocking 100 arms will be the reverse of that shown in dotted lines in Fig. 1, when the boat is turned in a direction opposite to that illustrated in dotted lines. The rollers 25 prevent any binding action between the rod 23 105 and the rocking arms, when the rocking arms are shifted from normal position. The weight 15 and arm 12, in connection with the rocking arms, permanently tend to right the boat on its keel. 110

What I claim is:

1. A life boat comprising a hull provided with a keel having a transverse opening, a weight and arm loosely connected to the hull and depending below the keel, a pair of vertically movable bars carried by the hull and having curved lower ends arranged in said opening, and rocking arms pivotally connected to the said ends and with the hull, and moving against opposite sides of said arm.
2. A life boat comprising a hull provided with a keel having a transverse opening, a weight and arm loosely connected to the hull and depending below the keel, a pair of vertically movable bars carried by the hull and having curved lower ends arranged in said opening, rocking arms pivotally connected to the said ends and with the hull, and moving against opposite sides of said arm, and

means for loosely connecting said rocking arms together.

3. A life boat comprising a hull provided with a keel having a transverse opening, a weight and arm loosely connected to the hull and depending below the keel, a pair of vertically movable bars carried by the hull and having curved lower ends arranged in said opening, rocking arms pivotally connected to the said ends and with the hull and moving against opposite sides of said arm, means for loosely connecting said rocking arms together, and means for limiting downward movement of said rods.

In testimony whereof I affix my signature 35
in the presence of two witnesses.

LADISLAUS PREICZER.
